Primary Examiner — Darlington Ly(74) *Attorney, Agent, or Firm* — Polson Intellectual Property Law, PC; Margaret Polson(57) **CLAIM**

The ornamental design for a childs bicycle, as shown and described.

DESCRIPTION

1. Childs bicycle

1.1 is a front elevation view of a childs bicycle showing our new design;

1.2 is a rear elevation view thereof;

1.3 is a left side elevation view thereof;

1.4 is a right side elevation view thereof;

1.5 is a top plan view thereof;

1.6 is a bottom plan view thereof; and

1.7 is a perspective view thereof.

The broken lines shown in the drawings illustrate portions of the child's bicycle that form no part of the claimed design.

1 Claim, 7 Drawing Sheets(56)
